OVERLOAD PROTECTION MECHANISM

Eugene M. Calkins, El Paso, Tex.

Application February 14, 1946, Serial No. 647,465

3 Claims. (Cl. 200—116)

1

The present invention relates to overload protection mechanism for use in electric circuits which mechanism includes a fuse for protection against short circuits and a resettable thermal controlled arrangement for opening the circuit against overload or "sneak" currents which although not strong enough to blow the fuse will if long continued cause injury to the apparatus connected with the line.

An object of the present invention is to provide an overload protection mechanism having non-disruptable separable parts for opening an electric circuit when the current in the line approaches a dangerous value.

Another object of the present invention is to provide mechanism operated by an increase in temperature above a predetermined value, to open an electric circuit, and which means is capable of being reset after the temperature drops.

A still further object of the present invention is to provide an improved universally applicable replacement mechanism suitable for use in existing types of explosion fuses and which can be reset after being opened, as it contains no part which is disrupted by overload conditions.

The invention has for an additional object the provision of an overload protection mechanism in which two contacts are normally retained in circuit relation by latch means, the latch means including a bimetal hook member subjected to the influence of heat generated by flow of current through the mechanism and operable on the occurrence of a temperature above a predetermined value to unlatch said contacts for separation thereof to provide a gap in the circuit.

Another and yet further object of the present invention is to provide an overload protection mechanism wherein a heating coil is provided for separating two latched parts to open an electric circuit on occurrence of a predetermined value current flow not in itself sufficient to blow the fuse.

A still further object of the present invention is to provide an overload protection mechanism having latch means normally engaged to hold the circuit closed and having a heating coil effective to separate said latch means on occurrence of line current beyond which continued safe operation is not assured.

A still further object of the present invention is to provide an overload protection mechanism having a contact carrying drop-out member normally held by latch means in circuit-closing relation and which is unlatched by means subjected to the influence of heat generated by the flow of

2

current through the mechanism, said member being relatchable after temperature drop to close the circuit through the mechanism.

Another and still further object of the present invention is to provide an overload protection mechanism having reusable or resettable circuit opening means to interrupt or open a circuit when an excess current flows through it.

A still further object of the present invention is to provide an overload protection mechanism having relatively movable line contacts normally held in circuit closing relation by latch means, and means subjected to the influence of heat generated by the flow of current through the mechanism operable on the occurrence of a temperature above a predetermined value to unlatch said contacts for separation thereof to open the circuit, said line contacts being returnable to circuit closing relation when the line temperature has dropped so that the contacts may again be in operative relationship.

The above, other and further objects of the present invention will be apparent from the following description and accompanying drawing.

An embodiment of the present invention is illustrated in the accompanying drawing and the views thereof are as follows:

Figure 1 is a view, partially in section and partially in elevation, of an explosion-type fuse utilizing an overload protection mechanism which includes the principal features of the present invention;

Figure 2 is a vertical sectional view through the mechanism of the present invention; and

Figure 3 is a fragmental elevational view of a part of the mechanism of the present invention, showing the short circuit blow-out fuse.

As shown on the drawing:

An explosion fuse structure is illustrated including a main tube or cartridge 5 of fiber or other suitable insulating material, which is threaded at its upper end to threadingly engage a metallic contact member or ferrule 6. The upper neck 7 of the member 6 is threaded to receive internal threads on a cap 8. The ferrule 6 and cap 8 are made of a conducting material, as the member 6 is adapted to engage a suitable clip or other mechanism for connecting the cartridge in circuit. Surrounding the lower end of the cartridge 5 is a ferrule 9 adapted to engage another clip or other contact member for completing a circuit.

The overload protection structure or refill unit designated generally as A, is positioned within the cartridge 5.

The structure A is shown as comprising a cas-

ing which may be formed in two parts, Figure 2 showing an upper part 10 and a lower part 11, arranged with the upper end of the lower part 11 overlapping the lower end of the upper part 10. The casing is made of insulating material, such as fiber or the like. The upper end of the casing is closed by a cap 12 of metal or other suitable conducting material which, when the fuse link structure A is installed in the cartridge 5, is clamped between the upper margin of the ferrule 6 and the cap 8 to establish electric contact between the ferrule and the cap 12.

As shown, disposed near the lower end of the upper part 10 of the casing is a collar 13, of insulating material, having a central opening 14 therein serving as a guide for a drop-out member such as a plunger 15 movable into and out of the lower open end of the casing.

Loosely mounted on pins 16 and 17, near the lower part of the casing, is a stationary contact 18. The contact may be mounted on the pins so as to move along them, and may be constrained away from the inner surface of the casing by a spring 19 which serves also to maintain electrical engagement between the contacts 18 and 20. Although the contact 18 has been mentioned as stationary, yet it may be movable, to a slight extent on the pins, the word "stationary" being used to signify that the contact remains stationary as far as displacement from the casing is concerned.

The plunger 15 is provided with a contact 20 to engage the stationary contact 18 in circuit closing relation.

The plunger or drop-out member 15 would drop out of the casing unless prevented or restrained.

The illustrated form of restraining means includes cooperating latching parts. The upper end of the plunger 15 may be formed with an annular groove 21 underneath a head portion 22, the head portion is shown as of frusto-conical form to guide the upper end of the plunger into the guide 13 when the plunger is applied to the casing, as will be more fully explained.

Attached to the cap 12 is a bimetallic strip or element 23 having a hook 24 at its lower end to engage underneath the head 22 of the plunger 15 when the plunger 15 has been moved into the casing, through its open lower end, to establish circuit-making relationship between the contacts 18 and 20.

Between the head 12 and the stationary contact 18 is a conductor 25 having a heating coil 26 formed in it, adjacent the cap 12, and surrounding the bimetallic element 23. The conductor continues downwardly through the guide collar 13 where it is electrically connected to the stationary contact 18. The conductor 25 is bent or otherwise arranged as to be out of the path of movement of the hook 24.

Carried by the plunger 15 and in electrical connection with the contact 20 is a conductor 27 terminating in a terminal 28. The terminal 28 is mounted on the plunger 15 as may be observed in Figures 1 and 3. Carried by the lower end of the plunger 15 is a pig tail conductor 29 an end of which is electrically connected to the ferrule 9 by means of a suitable set screw 30. Between the pig tail 29 and the conductor 27 is a weak link or short circuit blow-out fuse 31 calibrated to blow under short circuit. A binding post 36 connects the pig tail 29 to the link 31 and circuit through the mechanism.

The collar 13 in addition to serving as a guide

for the upper end of the plunger 15 when it is inserted in the casing may be useful to maintain the plunger substantially centrally of the casing when the plunger is latched so that its contact 20 is in electrical engagement with the contact 18.

For moving the plunger 15 downwardly, when the latch means are disengaged, I preferably utilize a spring 32 attached at its upper end as by a screw 33 to the plunger 15 and hooked at its lower end 34 over the margin of the lower open end of the casing. The spring 32 is tensioned when the plunger is in latched engagement with the hook 24 so that as soon as the latched engagement is disturbed the plunger is pulled downwardly by the spring thus separating the electric connection between the contacts 18 and 20 and dropping the plunger out of the casing.

The casing is provided with an opening 35 adjacent the hook 24 of the bimetal element 23 so that a tool may be inserted to disengage the hook 24 from the head 22 of the plunger 15 in the event it is desired to inspect the contact 20.

The bimetal element 23 and the heating coil 26 are so designed that the hook end 24 of the bimetal element will be removed from underneath the head 22 of the plunger 15 when the temperature in the zone of the heating coil 26 reaches a predetermined value whereupon the hook will become disengaged from the head 22 and the spring 32 will yank the plunger 15 down and out of the lower end of the casing thus opening the circuit between the contact engaging the upper ferrule 6 and the contact engaging the lower ferrule 9 of the cartridge 5.

The lower part 11 of the casing constitutes an arc shoot.

In order to reset the overload protection structure after it has been once opened all that is necessary to be done is for an attendant to enter the plunger 15 through the lower end of the casing and raise it through the guide collar 13 until its head 22 snaps over the hook 24 of the bimetal element. Because of the opening of the circuit the temperature in the heating coil 26 drops and the hook end of the bimetal element returns to its normal or latching position ready to engage the head 22 of the plunger.

It is to be observed that in the event of short circuits the weakened link 31 will blow as is usual. However the provision of the heating coil 26 takes care of sneak or other overload currents so that when these build up the temperature to a point which, if it increased, might cause damage to the apparatus connected to the line, the bimetal element 23 moves to unlatch the plunger 15 for its withdrawal from the tube and opening of the circuit in which the link structure is installed.

It will be observed that the overload protection structure of the present invention is one which may be manufactured at economical cost, is one in which the plunger and bimetal element may be relatched or reset whenever unlatched, without the replacement of some disrupted part, such as a fusible element. Of course, when the blow-out fuse 31 blows it has to be replaced, however the number of times the fuse link structure would function to open the circuit because of overload is greater than the number of times that the fuse 31 would blow under short circuit conditions. It may be understood that the structure of the present invention is a handy one and may be readily reset simply by returning the plunger 15 into the casing and raising it until its upper end hooks with the end of the bimetal element 23 whereupon the structure is ready for further use.

The relationship of the bimetal element 23 and the heating coil 26 determines the maximum capacity of the fuse link structure. Thus having constructed such a structure with a known capacity the structure may continue in use without any fear of burning out any of the equipment connected to the line as it is assured the circuit will open when the maximum capacity of the structure is reached, that is to say when the temperature of the heat generated in the heating coil 26 by the flow of sneak currents through it rises to the value where the hook end 24 of the bimetallic element is moved away from latched engagement with the head 22 of the plunger 15.

By "dangerous" value, used in connection with the temperature created by "sneak" or other overload currents, is meant any temperature beyond which the continued safe operation of apparatus connected in the line is not assured.

It will, of course, be understood that various details of construction may be varied through a wide range without departing from the principles of this invention and it is, therefore, not the purpose to limit the patent granted hereon otherwise than necessitated by the scope of the appended claims.

I claim as my invention:

1. An overload protection structure comprising a casing open at one end and closed at the other end, a plunger movable into and out of said casing through said open end, hook means for engaging said plunger to hold it in the casing, a first contact mounted within the casing, a second contact mounted on the plunger and in circuit closing engagement with said first contact when said plunger is engaged by said hook means, a conductor connected to said first contact, a second conductor connected to said second contact, a heating coil in said first conductor, said hook means comprising a bimetal element through said coil subjected to rise of temperature in said coil to become disengaged from said plunger, spring means for withdrawing said plunger when so disengaged, said spring means being attached at its upper end to a side of said plunger and removably engageable at its lower end over the lower edge of said casing to bias said plunger downwardly and a fusible link on said plunger in the circuit to said second contact for opening the circuit under short circuit conditions.

2. In combination with an explosion fuse cartridge having a separable ferrule at its upper end and a ring ferrule adjacent its lower end, an overload protection device comprising a tubular structure having a contact member at its upper end for electrical connection with the upper ferrule of the cartridge and open at its lower end, a contact member within said tubular structure mounted and guided for movement radially of said structure, a conductor joining said contact members in circuit relation, a drop-out plunger within said structure and movable axially thereof into and out of said structure through said open lower end, a contact member on said plunger engageable with said second mentioned contact member when said plunger is in place within said structure, means for latching said plunger in place in said structure, means within said structure encompassing the upper end of said

5 10 15 20 25 30 35 40 45 50 55 60 65 70

plunger to guide it into latching position, resilient means for ejecting said plunger from the tube of said structure when said latching means are released, said resilient ejecting means being disposed between said structure and the side of said plunger for fixed attachment to the side of said plunger and releasable attachment to the open lower end of said structure a conductor on said plunger including a pig tail connected to the ring ferrule on said cartridge to thereby electrically connect said first contact and said ferrule when said plunger is latched in place.

3. In combination with an explosion fuse cartridge having a separable ferrule at its upper end and a ring ferrule about the cartridge adjacent its lower end, an overload protection mechanism comprising a tubular structure having a contact member at its upper end for clamping engagement with the separable ferrule at the upper end of said cartridge and open at its lower end, a contact member within said structure mounted and guided for movement radially of said structure, a spring acting against said contact to urge it away from said tubular structure, a conductor joining said contact members in circuit relation, a drop-out plunger within said structure and movable axially thereof into and out of said structure through said lower open end, said plunger having a head at its upper end, a contact member on said plunger engageable with said second mentioned contact member when said plunger is in place within said structure, a hook engageable with the head of said plunger for latching said plunger in said structure with its contact against said second mentioned contact, a collar within said structure encompassing the upper end of said plunger to guide it into latching position, a spring connected between said plunger and tube for ejecting the plunger from the tube when said latching means are released, the conductor between said first and second contact members being coiled and constituting a heating coil, a bimetal member secured at one end to said first contact and supporting said hook at its other end and projecting through the coil in said first conductor, a conductor electrically connected with the contact member on said plunger and to the ring ferrule on said cartridge to thereby electrically connect said first contact member and said ferrule when said plunger is latched in place, and a fusible member in said last mentioned conductor adapted to blow under short circuit condition.
